(57) **CLAIM**

The ornamental design for a shaft attachable medical instrument, as shown and described.

DESCRIPTION

FIG. 1 is a front perspective view of a shaft attachable medical instrument according to the present invention.

FIG. 2 is a front view of the shaft attachable medical instrument of FIG. 1.

FIG. 3 is a rear view of the shaft attachable medical instrument of FIG. 1.

FIG. 4 is a left side view of the shaft attachable medical instrument of FIG. 1.

FIG. 5 is a right side view of the shaft attachable medical instrument of FIG. 1.

FIG. 6 is a top view of the shaft attachable medical instrument of FIG. 1; and,

FIG. 7 is a bottom view of the shaft attachable medical instrument of FIG. 1.

The dashed lines illustrate environment that does not form part of the claimed design. The dashed lines with brackets are symbolic breaks, and any portion of the shaft attachable medical instrument between the breakaways forms no part of the claimed design.
